PATRICK J. HOGAN, OF CINCINNATI, OHIO.

Letters Patent No. 88,712, dated April 6, 1869.

IMPROVED PLASTERING-TROWEL.

The Schedule referred to in these Letters Patent and making part of the same.

To all whom it may concern:

Be it known that I, PATRICK J. HOGAN, of Cincinnati, in the county of Hamilton, and the State of Ohio, have invented a new and useful Improvement in Plastering-Trowels, of which the following is a full and clear description, reference being had to the accompanying drawings, making part of this specification.

My invention relates to the manner of securing the handle to the blade of the trowel, and to the adjustability of the parts.

Figure 1 is a perspective view of my improved trowel.

Figure 2 is a longitudinal section of the same.

Figure 3 is a cross-section of the trowel.

A is the blade of the trowel, to which is secured, by rivets *a*, the longitudinal stiffening-rib B.

The standard C of the handle of the trowel is constructed with a foot, which dovetails into the rib B, upon which it may be moved, and secured by the set-screw *b*.

The set-screw *b* is tapped through the foot of the handle, and is caused to impinge upon the rib B, in order to secure a rigid connection of the blade and handle of the trowel.

When it is desirable to remove or replace either the blade or the handle of the trowel, the set-screw is removed, when the foot of the standard may be slipped along the rib B, and off, and the new handle or blade may be adjusted.

What I claim as new, and desire to secure by Letters Patent, is—

The combination of the blade A, when riveted to the rib B, with the dovetailed foot C, secured to and adjustable upon said rib by means of the set-screw *b*, substantially as described, as and for the purpose specified.

PATRICK J. HOGAN.
